(57) **CLAIM**

The ornamental design for a battery termination, as shown and described.

DESCRIPTION

FIG. 1 is a perspective view of the battery termination according to the present invention.

FIG. 2 is a top view of the battery termination shown in FIG. 1.

FIG. 3 is a side view of the battery termination shown in FIG. 1.

FIG. 4 is a rear view of the battery termination shown in FIG. 1.

FIG. 5 is a front view of the battery termination shown in FIG. 1.

FIG. 6 is a bottom view of the battery termination shown in FIG. 1; and,

FIG. 7 is a side view of the battery termination shown in FIG. 1.

The broken lines shown throughout the drawing figures are included for the purpose of illustrating portions of the article that form no part of the claimed design.
